LIGHTING FIXTURE

Albert V. Jernigan, Dallas, Tex.

Application December 14, 1949, Serial No. 6,615

Term of patent 14 years

(Cl. D48—23)

To all whom it may concern:

Be it known that I, Albert V. Jernigan, a citizen of the United States of America, residing at Dallas, in the county of Dallas and State of Texas, have invented a new, original, and ornamental Design for Lighting Fixture, of which the following is a specification, reference being had to the accompanying drawing, forming part thereof.

In the drawing:

Fig. I is a perspective view of a lighting fixture, showing my new design;

Fig. II is a top plan view of the lighting fixture; and

Fig. III is side elevational view of the lighting fixture taken from the back side of Fig. I.

The dominant features of my design reside in the portions shown by means of full lines in the drawing.

I claim:

The ornamental design for a lighting fixture, as shown and described.

ALBERT V. JERNIGAN.
